VANITY CASE CONSTRUCTION

Alfred F. Reilly, North Attleboro, Mass., assignor
to Evans Case Company, a corporation of Mass-
achusetts

Application July 11, 1936, Serial No. 90,139

16 Claims. (Cl. 132—83.1)

My present invention relates to the manufacture of novelty items, and has particular reference to a novel construction for a vanity case.

It is the principal object of my invention to provide a vanity case which occupies a small space, and which may be tightly sealed to retain face powder and the like.

Another object of my invention is to provide a simple construction which is readily manufactured and assembled, whereby the cost of manufacture is reduced and the price to the consumer is lowered.

With the above and other objects and other advantageous features in view, my invention consists of a novel arrangement of parts more fully disclosed in the detailed description following, in conjunction with the accompanying drawings, and more specifically defined in the claims appended thereto.

20 In the drawings:

Fig. 1 is a top plan view of the novel vanity case;

Fig. 2 is a view similar to Fig. 1, the cover being in open position;

25 Fig. 3 is a side elevation of Fig. 1, parts being broken away and in section to show the sealing interlock of the top and the base;

Fig. 4 is a plan view of the novel retainer ring blank;

30 Fig. 5 is a perspective sectional detail showing the manner of assembly of the vanity case base parts;

Fig. 6 is a perspective view of a modified construction; and

35 Fig. 7 is a perspective view of a further modified construction.

Referring to the drawings, the novel vanity case 10 includes a cover 11 and a base 12 which are hingedly connected by a hinge construction 40 of standard type 13, the base 12 having a latch 14 and the cover a cooperating spring catch 15 for releasably retaining the parts in closed relation. The cover 11, note Figs. 2 and 3, includes a disk of generally dished form 16, which may be 45 ornamented in any suitable manner, as by en- ameling, engraving or the like, and a central mirror 17 which is secured within an upstanding retaining flange 18, this retaining flange having generally rounded edges and functioning as a sealing element as hereinafter described.

The base 12 includes a novel lock ring 19 of generally U-shaped form, which is preferably stamped out of sheet metal, the novel ring having a downwardly extending support bar or band 50 20 which is preferably joined to the main portion

of the ring 19 by spaced integral connecting strips 21, whereby a plurality of elongated openings 22 between the bar and the main body of the lock ring is formed. The upper edge 23 and the lower edge 24 of the ring form clamping jaws 5 for lockingly retaining the upper edge of a piece of flexible impervious material 25, preferably of leather, which is so shaped that it provides a bag or pouch although made of a single piece of material without seams, folds or puckers. The 10 element 25 constitutes a pouch for the reception of loose powder and also for a powder puff, if desired, which may be of any suitable form. Preferably, the pouch is enclosed within a metal mesh pouch 26 in the form of a bag, made of 15 interconnected mesh elements 27, the upper row of elements having rings 28 attached thereto; a spiral connecting wire 29 passes through the rings 28 and around the bar 20 into the elongated openings 22 to lock the outer mesh bag to 20 the lock ring 19. As best disclosed in Fig. 5, the material 25 extends over the edge of the bar 20 whereby an annular inner edge 30 is formed, within which the flange 18 of the cover may snugly seat when the cover is in closed position and thus 25 securely seal the powder compartment. If desired the bar 20 may be circular, or may be bent into a channel or a closed hollow form.

It is thus evident that the novel construction utilizes an annular lock ring which may be and 30 preferably is formed of stamped metal and which has secured thereto a retaining bar around which a spiral wire is threaded for securing the outer mesh bag to the lock ring, the bar 20 extending sufficiently forwardly of the ring 19 to provide a 35 sturdy corner support for the flexible material 25 and thus permit sealing engagement of the depending cover flange with the edge 30 of the flexible material. The entire locking arrangement thus utilizes a single annular lock ring, 40 easily stamped out of sheet material, and functioning as a retainer for the upper edge of the flexible material, a lock support for the upper edge of the outer mesh bag, and a corner support for the flexible material edge within which the 45 cover flange seats.

If desired, a construction such as disclosed in Fig. 6 may be used, the annular member 31 being stamped from sheet metal and comprising a U-shaped ring 32 and a depending portion 33 terminating in an upwardly extending flange 34. The ring 32 has an upper edge 35 and a lower edge 36, slots 37 being formed in the lower edge, and aligned slots 38 being formed in the depending portion 33, whereby a support element 39 is 50 55

provided which is secured to the ring 32 by strips 40. A metallic mesh pouch 41 is locked to the member 31 by a spiral connecting wire 42 which passes around the support element 39 and 5 through rings or the like 43 secured to the upper portion of the mesh pouch, and a flexible pouch 44, preferably of leather, is seated within the mesh pouch and has its upper portion 45 gripped within the member 31, as by clamping contact 10 of the upper and lower edges, or of the upper edge and the support element and its connecting wire.

A simpler construction, suitable for inexpensive vanity cases, is illustrated in Fig. 7, the 15 annular member 46 being U-shaped, with its upper edge 47 extending beyond the lower edge 48, and having spaced openings, such as perforations 49, formed in the overhanging portion, whereby a metallic mesh pouch 50 may be connected to the upper edge by means of a spiral 20 connecting wire 51 which passes through the perforations and through suitable openings in the upper portion of the mesh pouch which as illustrated are provided by rings 52, and a flexible 25 lining or pouch 53 is mounted within the mesh pouch, its upper edge 54 being clamped between the upper and lower edges of the annular member 46.

Although I have described a specific constructional embodiment of my invention, it is obvious 30 that changes in the materials used, in the shape and relative proportion of the parts, and in the relative arrangements of the parts, may be made to suit the requirements for different vanity case 35 designs and for bags and cases in general, without departing from the spirit and the scope of the invention as defined in the amended claims.

I claim:

1. In an article of the class described, a lock 40 member, a bar depending from and secured to said lock member at spaced intervals, and a metallic mesh member having its edge portion secured to said bar.

2. In an article of the class described, a lock 45 ring, a ring element depending from and secured to said lock ring at spaced intervals, and a metallic mesh bag having its edge portion secured to said ring element.

3. In an article of the class described, a lock 50 member, a flexible member secured to said lock member, a bar depending from and secured to said lock member at spaced intervals, and a metallic mesh member having its edge portion secured to said bar for which the flexible member 55 acts as a lining.

4. In an article of the class described, a lock ring, a flexible pouch having its edge portion secured to said lock ring, a ring element depending from and secured to said lock ring at spaced 60 intervals, and a metallic mesh bag having its edge portion secured to said ring element.

5. In an article of the class described, a lock member having gripping edges, a flexible member secured to said lock member by gripping engagement of the lock ring edges therewith, a bar depending from and secured to said lock member at spaced intervals, and a metallic mesh member having its edge portion secured to said bar.

6. In an article of the class described, a lock 70 ring having gripping edges, a flexible pouch having its edge portion secured to said lock ring, a ring element secured to said lock ring at spaced intervals, and a metallic mesh bag having its edge portion secured to said ring element by

gripping engagement of the lock ring edges therewith.

7. In a vanity case, a lock ring having gripping edges, a ring element of smaller radius secured thereto and spaced therefrom, a flexible pouch 5 having its upper portion gripped between said lock ring gripping edges, and a metallic mesh pouch having its upper portion secured to said ring element.

8. In a vanity case, a lock ring having gripping edges, a ring element of smaller radius secured thereto and spaced therefrom, a flexible pouch having its upper portion gripped between said lock ring gripping edges, and a metallic mesh pouch having its upper portion secured to 15 said ring element by a spiral wire connector.

9. In a vanity case, a lock ring having gripping edges, a ring element of smaller radius secured thereto and spaced therefrom, a flexible pouch having its upper portion gripped between 20 said lock ring gripping edges, a metallic mesh pouch having its upper portion secured to said ring element, and a cover hingedly connected to said lock ring and having an annular flange adapted to seat in said flexible pouch adjacent the 25 upper edge of the ring element for sealing engagement therewith.

10. In a vanity case, a lock ring having gripping edges, a ring element of smaller radius secured thereto and spaced therefrom, a flexible pouch having its upper portion gripped between 30 said lock ring gripping edges, a metallic mesh pouch having its upper portion secured to said ring element by a spiral wire connector, and a cover hingedly connected to 35 said lock ring and having an annular flange adapted to seat in said flexible pouch adjacent the upper edge of the ring element for sealing engagement therewith.

11. In a vanity case, a lock ring having gripping edges, a ring element secured thereto by 40 spaced strips, said strips being generally in the plane of the lock ring and said ring bar being generally perpendicular to the plane of the lock ring, a flexible pouch having its edge portion gripped between the gripping edges of the lock 45 ring, and a metallic mesh pouch secured to said ring element.

12. In a vanity case, a lock ring having gripping edges, a ring element secured thereto by 50 spaced strips, said strips being generally in the plane of the lock ring and said ring bar being generally perpendicular to the plane of the lock ring, a flexible pouch having its edge portion gripped between the gripping edges of the lock 55 ring, and a metallic mesh pouch secured to said ring element by a spiral metallic element.

13. In a vanity case, a lock ring having gripping edges, a ring element secured thereto by spaced strips, said strips being generally in the plane of the lock ring and said ring bar being 60 generally perpendicular to the plane of the lock ring, a flexible pouch having its edge portion gripped between the gripping edges of the lock ring, a metallic mesh pouch secured to said ring element, and a cover hingedly connected to said ring element, and a cover hingedly connected to said lock ring and having an annular flange adapted to seat in said flexible pouch adjacent the upper edge of the ring element for sealing engagement therewith.

14. In a vanity case, a lock ring having gripping edges, a ring element secured thereto by spaced strips, said strips being generally in the plane of the lock ring and said ring bar being generally perpendicular to the plane of the lock ring, a flexible pouch having its edge portion 70 75

gripped between the gripping edges of the lock ring, a metallic mesh pouch secured to said ring element by a spiral metallic element, and a cover hingedly connected to said lock ring and having 5 an annular flange adapted to seat in said flexible pouch adjacent the upper edge of the ring element for sealing engagement therewith.

15. A vanity case lock ring blank comprising a lock ring having gripping edges and an inner 10 ring of smaller radius concentric with and se-

cured to the lower edge of the lock ring at spaced intervals.

16. A vanity case lock ring blank comprising a lock ring having gripping edges and an inner ring of smaller radius concentric with and se- 5 cured to the lower edge of the lock ring at spaced intervals by strips in the general plane of said lower edge, said inner ring depending from said strips.

ALFRED F. REILLY. 10
